UNITED STATES PATENT OFFICE.

JOHN HARRIMAN, OF MILWAUKEE, WISCONSIN.

THILL-CO尤LING.

SPECIFICATION forming part of Letters Patent No. 321,720, dated July 7, 1885.

Application filed February 24, 1885. (No model.)

To all whom it may concern:

Be it known that I, JOHN HARRIMAN, of Milwaukee, in the county of Milwaukee, and in the State of Wisconsin, have invented certain new and useful Improvements in Thill-Couplings; and I do hereby declare that the following is a full, clear, and exact description thereof.

My invention relates to thill-couplings for wagons, &c., and will be fully described hereinafter.

In the drawings, Figure 1 is a side view of my device, and Fig. 2 is a vertical section through the same at right angles to the axle, which latter is shown in cross-section in both figures.

A is the axle, and B is the thill-clip. C are the lugs that receive the eye of the thill-strap between them. Each lug C has a downwardly-inclined projection or jaw, C', in front that terminates in a screw-threaded pin, C'', and between these pins C'' and the projections or jaws C' the rubber cushion D is inserted and followed by a plate, E, the pins passing through the plate to take nuts a. Short flanges E' on the top and bottom of plate E hold the rubber cushion in place, and it (the cushion) is concaved to fit about the lower front portion of the eye F of the thill-strap F'.

In using my device the eye of the thill-strap is first inserted between the lugs C and secured by the bolt b and nut b'. The plate

E, with the cushion D held between its flanges, is next passed onto pins C'', and then the nuts a are screwed on and tightened until the cushion presses sufficiently against the eye F to prevent rattling, and then as the cushion wears it may be advanced by tightening the nuts as long as any of the cushion remains.

By my construction I not only provide a perfect anti-rattler, but also render the breaking of bolt b less liable, as the cushion will relieve the bolt of a great deal of the draft strain.

Having thus fully described my invention, what I claim as new, and desire to secure by Letters Patent, is—

In a thill-coupling, the combination of the thill-strap F', having eye F, thill-clip B, having lugs C rigid therewith, said lugs terminating in jaws C', and screw-threaded pins C'' solid therewith, and arranged at an angle to the line of projection of the lugs C, rubber cushion D, plate E, having short flanges E', and securing-nuts a, substantially as set forth.

In testimony that I claim the foregoing I have hereunto set my hand, at Milwaukee, in the county of Milwaukee, and State of Wisconsin, in the presence of two witnesses.

JOHN HARRIMAN.
